UNITED STATES PATENT OFFICE.

CHARLES BRAUN, OF BROOKLYN, NEW YORK.

FLOUR SIFTER.

Application filed January 20, 1921. Serial No. 438,589.

To all whom it may concern:

Be it known that I, CHARLES BRAUN, a citizen of the United States, and resident of the borough of Brooklyn, county of Kings, 5 State of New York, have invented certain new and useful Improvements in Flour Sifters.

This invention relates to improvements in flour sifters and has for its principal object 10 to provide a device which may be manipulated as well as supported in one hand.

Another object of the invention is to provide a flour sifter which may be cheaply and easily constructed and which will avoid 15 the necessity of using two hands to support and operate the same.

Still another object of the invention is to provide a device having a minimum number of parts, thereby cheapening the construction without interfering with the efficiency of its operation.

With these and other objects in view the invention consists of a novel construction, combination and arrangement of parts 25 which will be fully set forth in the following specification, claimed and illustrated in the accompanying drawings in which:—

Fig. 1 is a vertical sectional view through the sifter.

Fig. 2 is a top plan view thereof, referring to the drawings in detail the numeral 5 designates the body of the device which comprises a cylinder which is open on both ends as shown in the drawings. Secured 30 about midway of the cylinder is a hemispherical sifting member such as the screen 6, and extending diametrically through the cylinder at a point in line with the axis of the hemispherical screen 6 is a shaft 7, on 35 which the agitator to be more fully herein-after described is mounted. The shield 8, is secured to the interior of the cylinder and extends upwardly from the upper edge of screen 6 to the upper end of the cylinder 40 and forms the guide for the agitator operating spring.

The agitator above referred to is designated in its entirety by the numeral 9 and comprises a plurality of bowed arms 10, 50 from the ends of which are secured two hubs 11, arranged on opposite ends of the shaft 7. The body is provided with a handle 12, extending outwardly therefrom in a plane

from the longitudinal axis of the shaft 7 and in direct alinement with the shield 8 55 in order that the operating handle of the agitator may be within easy reach of the hand of the user.

In order to provide a means for manipulating the agitator a flat leaf spring 13, is 60 secured at one end to one of the arms 10, while the opposite end of said spring extends upwardly to space 14 within the shield 8, and is connected to the operating handle 15 provided at its upper end with a thumb 65 piece 16, which extends outwardly beyond the side edge of the cylinder in such a manner as to overhang handle 12.

In operating, upon applying pressure to the thumb piece 16, it will be obvious that 70 the handle 15 and spring 13 will be forced downwardly thereby causing the agitator 9, to rock on the shaft 7 in such a manner that the ends of the arms 10 will rub against the screen 6, thereby sifting the contents 75 of the cylinder. Upon releasing the pressure of the thumb piece 16, the spring 13 will tend to straighten and will impinge against the lower edge of the shield 8, thereby acting to return the agitator and handle 80 15 to original position or as shown in Fig. 1.

Obviously, repeated operation of the device will cause the agitator to rapidly oscillate and sift the contents of the cylinder 85 through the screen 6.

While in the foregoing there has been shown and described a preferred embodiment of this invention, it is to be understood that certain minor changes in the details of construction may be resorted to without departing from the spirit and scope of the invention as claimed.

What is claimed is:—

1. A flour sifter comprising a cylinder, a sifting screen arranged intermediate the 95 ends of the cylinder, a handle secured to and radiating from the cylinder, an agitator pivotally mounted within the cylinder for co-operation with the sifting screen, an agitator actuating handle slidably mounted 100 adjacent the first named handle, resilient means connecting the actuating handle with the agitator and a guide within said cylinder through which said handle is adapted to reciprocate, said guide retaining said resilient 105 means flexed to cause said actuating handle

2
to bear against the wall of the cylinder adjacent the handle.

2. A flour sifter comprising a cylinder, a sifting screen arranged intermediate the ends of the cylinder, an agitator pivotally mounted for co-operation with the screen, a vertical guide within the cylinder, a flat spring adjacent said guide and flexed there-

by and having one end secured to the agitator, and a nonflexible operating member ¹⁰ secured to the free end of said flat spring for operating said spring and said agitator.

Signed in the city, county and State of New York, this 18th day of January, 1921.

CHARLES BRAUN.
